UNITED STATES PATENT OFFICE.

WILLIAM H. R. TOYE, OF PHILADELPHIA, PENNSYLVANIA, ASSIGNOR, BY DIRECT AND MESNE ASSIGNMENTS, TO THE SIMULTANEOUS CHROMOGRAVURE PRINTING MACHINE AND MANUFACTURING COMPANY, OF CAMDEN, NEW JERSEY.

MULTIPLE-COLOR-PRINTING MACHINE.

SPECIFICATION forming part of Letters Patent No. 522,128, dated June 26, 1894.

Application filed November 30, 1891. Renewed December 12, 1893. Serial No. 493,493. (No model.) Patented in England May 13, 1892, No. 9,122.

To all whom it may concern:

Be it known that I, WILLIAM H. R. TOYE, a citizen of the United States, residing in the city of Philadelphia, in the county of Philadelphia and State of Pennsylvania, have invented a new and useful Improvement in Multicolor-Printing Machines, (for which a patent, No. 9,122, dated May 13, 1892, has been granted to me, with others, in Great Britain,) of which the following is a true and exact description, reference being had to the accompanying drawings, which form a part thereof.

My invention relates to printing presses, particularly to such as are designed to print in colors, and has for its main object to provide a press wherein very exact register can be obtained, and consists mainly in a suitable construction of carrier device consisting of a number of separate blocks abutted end to end connected by a suitable band or bands, some of which blocks are provided with gripper mechanisms for the purpose of seizing and carrying forward the sheet.

My invention also consists in combining a suitable flexible carrier composed of separate links, some of which are toothed, with a printing couple having teeth, adapted to engage with the teeth on the carrier, and means, independent of the flexible carrier, for driving the printing couple; and further, in various improvements more specifically pointed out in the claims appended to and forming part of this specification.

My invention will be best understood as described in connection with the accompanying drawings, in which—

Figure 1 is a side view of a multiple color press embodying my invention; Fig. 2 an enlarged detail view of a portion of the flexible carrier and the support therefor. Fig. 3 is a vertical section of one of the blocks, which go to make up the flexible carrier, on the line $\alpha\alpha$ of Fig. 2. Fig. 4 is a side view of a press having but a single printing couple embodying my invention. Fig. 5 is an end elevation of the press showing the gripper mechanisms attached to the carrier. Fig. 6 is a side view

on an enlarged scale of one of the blocks which go to make up the flexible carrier, showing the means for taking up any slack in the bands which hold the carrier together, and also the cam for operating the gripper mechanisms.

Referring to the drawings, A designates the frame of the machine in which is mounted the printing couple, consisting preferably of a type cylinder B and an impression cylinder C. One or more pairs of said cylinders may be employed, according to the number of colors to be printed, and each printing cylinder is interchangeable in position with its impression cylinder, owing to its being mounted on bearings or boxes B^X, which are interchangeable and adjustable in openings in the frame A on opposite sides of travel of the material on which the printing is to be done, so as to adapt it for work on either side of the sheet. Each printing cylinder is supplied with the proper inking rollers of any well known or usual construction, as shown at D and E. The frame A is formed of intermediate and end sections, the intermediate section being provided with bearings for the said cylinders; and a machine for printing more than one color is made by attaching two or more of said intermediate sections with said end sections.

In order to insure that the carrier shall move exactly synchronously with the printing couple, I secure a wheel or wheels F on the shaft which carries one member of the printing couple, preferably the printing or type cylinder, and I provide registering devices on said wheel or wheels and corresponding devices on the carrier, so that when these registering devices are engaged the cylinder and flexible carrier will move together. As shown, I provide every eighth block of the set, which make up the flexible carrier, with teeth T and provide teeth F' on one-eighth of the periphery of the wheel F, it of course, being obvious that any other part of the wheel and carrier may be provided with intermeshing gear if desired. The toothed blocks are

preferably those which carry the gripper mechanism.

Each of the cylinders above the flexible carrier is geared with its companion cylinder 5 below the carrier by means of gears B^3 secured on the shafts of said cylinders outside of the frame A, and in the compound printing press, shown in Fig. 1, the printing and impression cylinders above the registering 10 band are connected by means of the intermediate gear wheel F^2 , suitably mounted on the frame A and meshing with gear wheels on the shafts of said cylinder. To support the carrier at the ends of the frame I provide supports, 15 preferably consisting of polygonal pulleys K J, the two pulleys K at one end of the frame being connected as by a drum H and the pulleys J by a drum G. The drum H is conveniently connected with the adjacent cylinder 20 within the path of travel of the flexible carrier by means of an intermediate gear wheel 1 suitably journaled on the frame A, and which meshes with the gear wheel D^3 on the shaft of said drum H.

Power is communicated to the multiple machine by means of the driving belt 3 and a pulley on the shaft of the gear wheel F^2 , or, if desired, the machine may be driven by a belt 2 on a pulley on the shaft of the gear 25 wheel 1. In the press shown in Fig. 4 the driving wheel 7 is on the shaft of the intermediate gear wheel; it will of course be noted that if the drum H is to be connected with a primary cylinder or with different sized impression cylinders within the carrier, that 30 different sized intermediate gear wheels will be required. The various sections of the frame are connected by means of fish plates 35 which are secured by bolts or rivets to parts of adjacent sections, as shown in Fig. 4. The outer ends of the impression cylinders are provided with shoulders which furnish support for the flexible carrier in its travel. When the cylinder is placed below the path 40 of travel of the carrier the wheels F are removed from the journals of the cylinder and disks B^2 are placed upon these journals in their places, which disks form supports for the carrier corresponding to shoulders E^4 45 upon the impression cylinder.

The flexible carrier to which the gripper mechanisms are secured consists of a series of blocks N which are connected together in any suitable way, but in order to prevent the 50 wear and resulting lack of register which results if the blocks are pivoted or hinged together I prefer to connect them in the manner shown, wherein the blocks are abutted end to end and are held together by a suitable 55 flexible band or bands P. These bands may be strips or lengths of thin steel, or indeed, ordinary rope may be employed, but I prefer to use wire cables as shown, one on each side of the series of blocks. To accommodate 60 these cables I prefer to provide the blocks with grooves in their sides, as best shown in Fig. 3, and bars Q may be secured across said

grooves to retain the bands or cables in place. The blocks are preferably provided with intermeshing teeth S in their ends so as to hold 70 the blocks in alignment but permit them to turn freely one on the other. In order to positively drive the carrier I prefer to provide the blocks with sockets or recesses 6 which are adapted to be engaged by suitable studs or 75 teeth R on the supporting pulleys J K. These supporting pulleys are preferably polygonal, octagonal in the present instance, and each face of the support is equal in length to the length of a block, so that each side in turn 80 supports a single block. I also provide brackets V secured to the frame of the machine for supporting the carrier between the various cylinders and prevent sagging.

The gripper mechanisms may be of usual 85 and well known form, having the grippers extending across the machine, from side to side, see Fig. 5, so as to seize the paper or other material on which the printing is done, and, as shown in the drawings, they consist, as 90 usual, of a cross bar W, strikers Y, spring Z and the grippers A'.

In order to hold the blocks firmly together and to take up for wear I provide means for adjusting the length of the bands which hold 95 the blocks together, very convenient means for so doing are shown in Fig. 6 where the ends of the cables P are shown secured in sockets B^2 and C^2 ; the sockets B^2 are shown stationary and the sockets C^2 movable, the 100 block N has an abutment E² through which projects a screw threaded stem D² secured to the socket C^2 ; by means of a nut F² the socket C^2 is drawn up, and the length of the cable P 105 adjusted.

If it should become necessary to print a sheet in two full colors at one passage through the machine, two intermediate sections with the end sections of the primary machine are bolted or attached together. This duplication of the primary machine may be carried on indefinitely, thereby forming machines for printing any number of colors desired on either or both sides of the sheet.

By forming the frame in sections, the same 115 may be made of different lengths by combining different numbers of primary machines according to the number of colors and the kind of work required.

It will be noticed, that, as shown in the 120 drawings, the faces of the wheels J and K are eight in number, and the wheel on the printing cylinder has one eighth of its periphery cogged or toothed, whereby but a single block 125 contacts with the wheel of the printing cylinder in a revolution of the same but the faces of the wheels J and K may be of a different number and the blocks made to correspond therewith, and the toothed portion of the cylinder wheel made to correspond with the 130 block; it is obvious that means other than cylinders might be employed as the printing couple without departing from the spirit of my invention.

Having now described my invention, what I claim as new, and desire to secure by Letters Patent, is—

1. In a printing machine the combination with a printing couple, of a flexible carrier composed of separate links, some of which are toothed and adapted to engage with gear on the printing couple, supports for said carrier, and means independent of the carrier for driving the printing couple.
2. In a printing press the combination with one or more printing couples consisting of type and impression cylinders, of a flexible carrier consisting of a number of blocks having sockets therein, a band or bands for connecting said blocks together and supporting wheels for the carrier having studs adapted to engage with the socket in the blocks.
3. In a printing press the combination with one or more printing couples consisting of type and impression cylinders, of a flexible carrier consisting of a number of blocks having sockets therein, a band or bands for connecting said blocks together and polygonal sprocket wheels having studs adapted to engage with the sockets in the blocks.
4. In a printing machine a flexible carrier for conveying sheets to be printed between a printing couple, said carrier consisting of a number of blocks abutted together, end to end, a band or bands for holding said blocks together, and gripper mechanisms carried by certain of said blocks.
5. In a printing machine a flexible carrier for conveying sheets to be printed between a printing couple, said carrier consisting of a number of blocks abutted together, end to end, and having intermeshing teeth S, a band or bands for holding said blocks together, and gripper mechanisms carried by certain of said blocks.
6. In a printing machine a flexible carrier for conveying sheets to be printed between a printing couple, said carrier consisting of a number of blocks abutted together end to end, a band or bands for holding said blocks together, means for adjusting the length of said bands and gripper mechanisms carried by certain of said blocks.
7. In a printing machine a flexible carrier for conveying sheets to be printed between a printing couple, said carrier consisting of a number of blocks abutted together end to end, and having intermeshing teeth S, a band or bands for holding said blocks together, means

for adjusting the length of said bands, and gripper mechanisms carried by certain of the blocks.

8. In a printing press the combination with a flexible carrier for conveying sheets between a printing couple and consisting of a number of blocks having sockets thereon a band or bands for connecting said blocks, of supports for the carrier having studs adapted to engage with the sockets in the blocks. 65

9. In a printing press the combination with a flexible carrier for conveying sheets between a printing couple and consisting of a number of blocks having sockets therein and a band or bands for connecting said blocks, of polygonal supports for the carrier having studs adapted to engage with the sockets in the blocks. 70

10. In a flexible carrier for conveying the sheets to be printed between a printing couple, a number of blocks abutted together, grooves in the sides of said blocks, a band or bands adapted to fit in the grooves and hold the blocks together and gripper mechanisms carried by some of the blocks. 75

11. In a flexible carrier for conveying the sheets to be printed between a printing couple, a number of blocks abutted together, grooves in the sides of said blocks, a band or bands adapted to fit in the grooves and hold the blocks together, nuts fitting on the end of the bands for adjusting their length and gripper mechanisms carried by some of the blocks. 80

12. In a printing press the combination with type and impression cylinders constituting a printing couple, and means for driving the same, of a flexible carrier consisting of blocks, abutted end to end a band or bands for connecting said blocks and gripper mechanisms carried by certain of the blocks and supports 95 for said carrier journaled on the frame.

13. In a printing press the combination with type and impression cylinders constituting a printing couple and means for driving the same, of a flexible carrier consisting of blocks, abutted end to end an adjustable band or adjustable bands for connecting said blocks and gripper mechanisms carried by certain of the blocks and supports for said carrier journaled on the frame. 100
